UNITED STATES PATENT OFFICE

KELLAR STEM, OF HASTINGS, MICHIGAN, ASSIGNOR TO GRAND RAPIDS BOOKCASE & CHAIR COMPANY, OF HASTINGS, MICHIGAN

DESIGN FOR A CABINET

Application filed July 9, 1931. Serial No. 40,476. Term of patent 3½ years.

To all whom it may concern:

Be it known that I, KELLAR STEM, a citizen of the United States, residing at Hastings, in the county of Barry and State of Michigan, have invented a new, original, and ornamental Design for a Cabinet, of which the following is a specification, reference being had to the accompanying drawing, forming part thereof.

The figure is a perspective view of a cabinet showing my new design.

I claim:

The ornamental design for a cabinet as shown.

KELLAR STEM.
